UNITED STATES PATENT OFFICE.

LIAM REAMONN MacEOCAGAIN, OF NEW YORK, N. Y.

DESIGN FOR A STATUE OR STATUETTE.

Application filed May 23, 1922. Serial No. 2,389. Term of patent 14 years.

To all whom it may concern:

Be it known that I, LIAM REAMONN MacEOCAGAIN, a subject of the King of Great Britain, residing at the city of New York, borough of Manhattan, in the county and State of New York, have invented a new, original, and ornamental Design for a Statue or Statuette, of which the following is a specification, reference being had to the accompanying drawings, forming part thereof.

The figure is a view in elevation of said statuette or statue showing my design.

I claim:

The ornamental design for a statue or statuette as shown.

LIAM REAMONN MacEOCAGAIN.
